HIGH-REACTANCE BALLAST TRANSFORMER

Andrew Schevtchuk, Fort Wayne, Ind., assignor
to General Electric Company, a corporation of
New York

Application November 26, 1952, Serial No. 322,744

8 Claims. (Cl. 336—155)

1

This invention relates to stationary electrical induction apparatus and more particularly to high reactance ballast transformers for use with fluorescent lamps.

Fluorescent lamps are arc discharge devices and thus their internal resistance decreases as the current flow therethrough increases. It is therefore necessary in the installation of fluorescent lamps to provide a current limiting device to limit the current flow through the lamp to a safe value. In addition, it may also be desirable to provide a higher voltage for initially starting or causing a discharge in the lamp than is conveniently available. When fluorescent lamps are operated on alternating current, it is conventional practice to provide a single high reactance ballast transformer to perform these two functions, i. e., current limiting and the provision of a high initial starting voltage. Such a transformer provides a high open circuit voltage for starting and also, by virtue of its high reactance, provides impedance during normal operation to limit the current flow.

A high reactance transformer is one in which the primary and secondary windings are loosely coupled so that when the transformer is carrying load, there is a substantial amount of leakage flux and the voltages induced in the windings by this leakage flux cause the transformer to have a relatively high effective series reactance or what is commonly known as leakage reactance. The conventional way of constructing such a transformer is to arrange the primary and secondary windings on different parts of the magnetic core and to provide a magnetic shunt between the windings thereby providing a path for the leakage flux. This shunt is usually provided with an air gap so calibrated that the open circuit secondary winding voltage of the transformer will be limited to a desired value. It is possible to operate two fluorescent lamps from a single ballast by providing two secondary windings with a common primary winding. In such installations, it is conventional practice to insert a capacitor in circuit with one of the lamps thereby causing that lamp to draw leading current whereas the other lamp will draw a lagging current due to a leakage reactance and inductive reactance of the secondary winding to which it is connected. Operation of one lamp with leading current and the other lamp with lagging current improves the over-all power factor of the ballast and further, when the two lamps are physically located close together, the stroboscopic effect of the light produced by the lamps is materially decreased.

It is well known that lagging current flowing

2

in a transformer secondary winding will produce leakage flux which in effect bucks the flux produced by the primary winding so that the net output voltage of a lagging current secondary under load is lower than the open circuit induced voltage. In the case of a secondary winding having leading current flowing therein, however, the leakage flux produced thereby aids the primary flux thereby producing a higher output voltage under load than is produced under open circuit conditions. It is therefore necessary to design the ballast to accommodate the increase in voltage in the leading secondary winding without saturating the core. This has been accomplished in the past by placing a series air gap in the center leg of the core in order to limit the amount of primary flux produced by the primary winding. Thus, if sufficient turns are wound on the core so that the core does not saturate under load, the induced voltage in the secondary windings under open circuit conditions will not be excessive since the series gap will limit the primary flux. Another method of accommodating the high level flux in the leading secondary region of the core is to operate the core under the primary coil and lead coil at such a low flux density under open circuit conditions that the induced open circuit secondary voltages are not excessive and the core has sufficient flux capacity in the region of the primary winding and lead secondary winding for the flux produced under normal running conditions. Such an arrangement is shown in application Serial No. 155,226, filed April 11, 1951, of Wesley W. Brooks and Andrew Schevtchuk, assigned to the assignee of the present application, and now abandoned. The objection to the construction of this type is the fact that the core is not symmetrical thereby making assembly more difficult. It is desirable therefore to provide a symmetrical high reactance ballast transformer which will accommodate the flux in the region of the lead secondary winding under operating conditions and which is easy to manufacture.

It is therefore an object of this invention to provide an improved ballast transformer incorporating the desirable features set forth above.

Another object of this invention is to provide improved core for a high reactance ballast transformer designed to accommodate the flux in the region of a leading current secondary winding.

A further object of this invention is to provide an improved fluorescent lamp circuit utilizing a ballast providing the desirable features enumerated above.

Further objects and advantages of this inven-

55

tion will become apparent and invention will be better understood by reference to the following description and the accompanying drawing, and the features of novelty which characterize this invention will be pointed out with particularity in the claims annexed to and forming a part of this specification.

In accordance with this invention, a high reactance ballast transformer is provided for a two-lamp fluorescent circuit of the type having a leading current lamp and a lagging current lamp, in which the primary flux produced by the primary winding is caused to follow parallel paths, one path linking with one secondary winding and the other path linking with another secondary winding. The core of the ballast is further arranged so that the leakage flux produced by each secondary winding is segregated from the two parallel paths of primary flux and from the leakage flux of the other winding. In this way, the primary and leakage flux in the region of the lead secondary winding is accommodated and either secondary winding may be connected as a leading current winding.

In the drawing, Fig. 1 is a side elevation of view, partly in section, illustrating the improved high reactance ballast transformer of this invention; and

Fig. 2 is a schematic illustration of a two-lamp ballast circuit utilizing the improved ballast transformer of this invention.

Referring now to the drawing, there is shown a magnetic core generally identified as 1 having a straight center winding leg 2. Center leg 2 is longitudinally split into two sections 3 and 4 defining a longitudinal air gap 5 therebetween. Two E-shaped yoke members 6 and 7 are provided and arranged respectively on either side of the center leg member 2, as will be hereinafter more fully described. All of the members comprising the core 1 are formed of a plurality of relatively thin laminations of magnetic material. The air gap 5 is maintained and the yoke members 6 and 7 are held in assembled relation by suitable end clamps well known in the art (not shown). While the center leg 2 of Fig. 1 is shown as incorporating longitudinal air gap 5, the center leg member 2 may be formed as a single part thus omitting the longitudinal air gap 5.

The lower yoke 6 is provided with a first end leg 8 having a butt joint with end 9 of center leg member segment 4 and another end leg 10 defining an air gap 11 with the other end 12 of center leg member segment 4. End legs 8 and 10 are joined by a bridging portion 13 and a leakage leg 14 is formed on bridging portion 13 forming a butt joint with center leg segment 4. Leakage leg 14 is displaced from the transverse center line of the core thus defining a single coil receiving window 15 with end leg 10 and a double coil receiving window 16 with end leg 8.

The upper yoke member 7 is arranged oppositely to the lower yoke 6, i. e., with one end leg 17 forming a butt joint with end 18 of center leg member segment 3 and with its other end leg 19 forming an air gap 20 with end 21 of center leg member segment 3. End legs 17 and 19 of upper yoke members 7 are joined by bridging portion 22 with leakage leg 23 forming a butt joint with center leg member segment 3. Here again, leakage leg 23 is displaced from the transverse center line of the device thereby forming a single coil receiving window 24 with end leg 19 and a double coil receiving window 25 with end

leg 17. It is thus clearly seen that end leg 8 of lower yoke member 6 abuts one end of center leg member 2 while end leg 17 of the upper yoke member 7 abuts the other end of center leg member 2 and that end leg 10 of lower yoke member 6 forms an air gap with the end of center leg member 2 which is abutted by end leg 17 and end leg 19 forms an air gap with the end of center leg member 2 abutted by end leg 8. It will also be seen that the double coil receiving window 16 of lower yoke member 6 overlaps the double coil receiving window 25 of upper yoke member 7 while the single coil receiving windows 15 and 24 respectively overlap double coil receiving windows 25 and 16.

Three electrical windings or coils are positioned on center leg 2 including primary winding 26 and secondary windings 27 and 28. It will be readily seen that primary winding 26 is positioned in both double coil receiving windows 16 and 25 while secondary winding 27 is positioned in single coil receiving window 15 and double coil receiving window 25 and the other secondary winding 28 is positioned in single coil receiving window 24 and double coil receiving window 16. Referring briefly to Fig. 2, it will be seen that primary winding 26 is adapted to be connected to an external source of alternating current (not shown) by lines 29 and 30. A first fluorescent lamp 31 is connected across primary winding 26 and secondary winding 28 by means of lines 32 and 33, thus making secondary winding 28 the lagging current secondary and other fluorescent lamp 34 is connected across primary winding 26 and secondary winding 27 by lines 32 and 35. A suitable capacitor 36 is arranged in series with line 35 thus making winding 27 the leading current secondary winding. As will be pointed out hereinafter, capacitor 36 could have been inserted in line 33 rather than line 35 since either secondary winding 27 or secondary winding 28 may serve as the leading current secondary winding.

Assuming now that primary winding 26 is connected to a source of alternating current across lines 29 and 30 and that lamps 31 and 34 are not connected to secondary windings 27 and 28, i. e., the open circuit condition, and referring again to Fig. 1, the primary flux divides equally between two parallel magnetic paths, one being shown by arrows 37 and the other by arrows 38. It will be seen that the primary flux in the upper yoke section 7 proceeds down in leg 17 into center leg section 3, thence up into leakage leg 23 and then into bridging member 22 back into end leg 17. No appreciable amount of this primary flux will link the portion of secondary winding 28 occupying single coil window 24 by virtue of the presence of air gap 20 between end leg 19 and single leg member segment 3. It will be seen however that the primary flux 37 does link that portion of secondary winding 27 positioned in double coil window 25. The primary flux 38 enters end leg 8 of lower yoke member 6 from single leg member segment 4 passing next into bridging portion 13 and thence through leakage leg 14 back into center leg member segment 4. Here again, the primary flux 38 does not link the portion of secondary winding 27 positioned in single coil window 15 because of the presence of air gap 11 between end leg 10 and single leg segment 4. Primary flux 38 does however link the portion of secondary winding 28 positioned in double coil window 16. It will now be seen that the two parallel paths of primary flux respectively link each of the secondary windings, primary

flux 37 linking the portion of secondary winding 27 positioned in double coil window 25 and primary flux 38 linking the portion of secondary winding 28 positioned in double coil window 16.

The parallel primary fluxes 37 and 38 induce sufficient voltages in secondary coils 27 and 28 to provide for starting the lamps 31 and 34. As soon as the lamps fire however, load current is drawn through the secondary windings 27 and 28. In the leading lamp circuit, the voltage across coil 27 increases as the lead lamp current flows through the coil and this current produces leakage flux. This flux takes two paths, that shown by arrows 39 in upper yoke member 7 and center leg member segment 3 and by arrows 40 in lower yoke member 6 and center leg member segment 4. Here again it is seen that the leakage flux is split in two paths, the leakage flux 39 following the same path and the same direction as the primary flux 37 while the flux 40 follows a new path through bridging portion 13 and leg 10 across air gap 11 and through center leg member segment 4 back into leakage leg 14 and bridging portion 13. It is thus seen that only a portion of the leakage flux produced by lead secondary winding 27 occupies the same portion of the core as the primary flux 37 thus permitting the use of less iron in the core than would be required to accommodate both lead leakage flux and primary flux if both fluxes were required to traverse the same magnetic section. Furthermore, the provision of the air gap 11 in the magnetic path of lead leakage flux 40 causes the lead secondary winding 27 to act as a reactor thus controlling the current in the circuit of lead lamp 34.

In the circuit of lag lamp 31, the action is similar although the voltage across lag secondary coil 28 is not as high as the voltage across lead secondary coil 27. Here, the leakage flux produced by lag secondary winding 28 again follows two paths, one indicated by arrows 41 flowing in the same path as but bucking the primary flux 38 and the other shown by the arrows 42 flowing in a path previously unoccupied by flux, i. e., through center leg member segment 3, leakage leg 23, bridging portion 22, end leg 19 and finally air gap 20 back into center leg segment 3. Here again the provision of air gap 20 in the path of leakage flux 42 serves to limit the current to the lag lamp 31.

As pointed out above, the longitudinal air gap 5 in the center leg 2 is not necessary for satisfactory operation and thus a solid laminated center leg can be provided instead of the split center leg shown in Fig. 1. It will also be apparent that this improved ballast transformer may be used in series lead circuits as well as lead-lag circuits.

While I have shown and described a specific embodiment of this invention, further modifications and improvements will occur to those skilled in the art and I therefore intend in the appended claims to cover all modifications which do not depart from the spirit and scope of this invention.

What I claim as new and desire to secure by Letters Patent of the United States is:

1. A high reactance ballast transformer for two fluorescent lamps comprising a magnetic core having a straight center winding leg and two E-shaped yoke members each having two end legs and a leakage leg intermediate said end legs defining two coil windows, and a primary coil and two secondary coils on said center leg, said primary coil being positioned in a first coil window of each of said yoke members, one of said secondary coils being positioned in the first coil

window of one of said yoke members and the other of said secondary coils being positioned in the first coil window of the other said yoke members whereby the primary flux divides in parallel paths each linking one secondary coil, said one secondary coil being also positioned in the second coil window of said other yoke member and said other secondary coil being also positioned in the second coil window of said one yoke member whereby the leakage flux of each of said secondary coils is isolated from said primary flux and from the leakage flux of the other of said secondary coils.

2. A high reactance ballast transformer for two fluorescent lamps comprising a magnetic core having a straight center winding leg and two E-shaped yoke members each having two end legs and a leakage leg intermediate said end legs defining two coil windows, and a primary coil and two secondary coils on said center leg, said primary coil being positioned in a first coil window of each of said yoke members, one of said secondary coils being positioned in the first coil window of one of said yoke members and the other of said secondary coils being positioned in the first coil window of the other said yoke members whereby the primary flux divides in parallel paths each linking one secondary coil, said one secondary coil being also positioned in the second coil window of said other yoke member and said other secondary coil being also positioned in the second coil window of said one yoke member whereby the leakage flux of each of said secondary coils is isolated from said primary flux and from the leakage flux of the other of said secondary coils, one end leg of one of said yoke members defining an air gap with one end of said center leg and one end leg of the other of said yoke members defining another air gap with the other end of said center leg thereby causing said secondary coils to act as reactors.

3. In a high reactance ballast transformer for two fluorescent lamps, a magnetic core having a straight center winding leg and two E-shaped yoke members, one of said yoke members having one of its end legs abutting one end of said center leg and the other of its end legs defining an air gap with the other end of said center leg, the other of said yoke members having one of its end legs abutting said other end of said center leg and its other end leg defining another air gap with said one end of said center leg, each of said yoke members having a leakage gap leg abutting said center leg and defining a single coil receiving window with said air gap defining end leg and a double coil receiving window with said abutting end leg.

4. In a high reactance ballast transformer for two fluorescent lamps, a magnetic core having a straight center winding leg and two E-shaped yoke members, one of said yoke members having one of its end legs abutting one end of said center leg and the other of its end legs defining an air gap with the other end of said center leg, the other of said yoke members having one of its end legs abutting said other end of said center leg and its other end leg defining another air gap with said one end of said center leg, each of said yoke members having a leakage gap leg abutting said center leg and defining a single coil receiving window with said air gap defining end leg and a double coil receiving window with said abutting end leg, each of said yoke members being disposed with its single coil receiving window overlapping one end of a double coil receiving window

of the other of said yoke members and with the other end of its double coil receiving window overlapping the other end of the double coil receiving window of the other of said yoke members whereby a primary coil may be arranged on said center leg and positioned in each of said double coil receiving windows and two secondary coils may be arranged on said center leg and respectively positioned in one single coil receiving window and one double coil receiving window.

5. In a high reactance ballast transformer for two fluorescent lamps, a magnetic core having a straight center winding leg and two E-shaped yoke members, said center leg being longitudinally split into two spaced apart segments defining a longitudinal air gap therebetween, one of said yoke members having one of its end legs abutting one of said center leg segments adjacent one end of said center leg and the other of its end legs defining an air gap with said one center leg segment adjacent the other end of said center leg, the other of said yoke members having one of its end legs abutting said other center leg segment adjacent said other end of said center leg and its other end leg defining another air gap with said other center leg segment adjacent said one end of said center leg, each of said yoke members having a leakage leg respectively abutting said center leg segments 30 and defining a single coil receiving window with said air gap defining end leg and a double coil receiving window with said abutting end leg.

6. A high reactance ballast transformer for two fluorescent lamps comprising a magnetic core having a straight center winding leg and two E-shaped yoke members, one of said yoke members having one of its end legs abutting one end of said center leg and the other of its end legs defining an air gap with the other end of said center leg, the other of said yoke members having one of its end legs abutting said other end of said center leg and its other end leg defining another air gap with said one end of said center leg, each of said yoke members having a leakage leg abutting said center leg and defining a single coil receiving window with said air gap defining end leg and a double coil receiving window with said abutting end leg, a primary coil on said center leg and adapted to be connected to an external source of alternating current, said primary coil being positioned in said double coil receiving window of both of said yoke members, a first secondary coil on said center leg positioned in said single coil receiving window of said one of said yoke members and in said double coil receiving window of said other yoke member, and a second secondary coil on said center leg positioned in said single coil receiving window of said other yoke member and in said double coil window of said one yoke member.

7. A high reactance ballast transformer for two fluorescent lamps comprising a magnetic core having a straight center winding leg and two E-shaped yoke members, one of said yoke members having one of its end legs abutting one end of said center leg and the other of its end legs defining an air gap with the other end of said center leg, the other of said yoke members hav-

10

ing one of its end legs abutting said other end of said center leg and its other end leg defining another air gap with said one end of said center leg, each of said yoke members having a leakage leg abutting said center leg and defining a single coil receiving window with said air gap defining end leg and a double coil receiving window with said abutting end leg, each of said yoke members being disposed with its single coil receiving window overlapping one end of the double coil receiving window of the other of said yoke members and with the other end of its double coil receiving window overlapping the other end of the double coil receiving window of the other of said yoke members, a primary coil on said center leg and adapted to be connected to an external source of alternating current, said primary coil being positioned in said double coil receiving windows of both of said yoke members, a first secondary coil on said center leg positioned in said single coil receiving window of said one of said yoke members and in said double coil receiving window of said other yoke member, and a second secondary coil on said center leg positioned in said single coil receiving window of said other yoke member and in said double coil receiving window of said one yoke member.

8. A high reactance ballast transformer for two fluorescent lamps comprising a magnetic core having a straight center winding leg and two E-shaped yoke members, said center leg being longitudinally split into two spaced apart segments defining a longitudinal air gap therebetween, one of said yoke members having one of its end legs abutting one of said center leg segments adjacent one end of said center leg and the other of its end legs defining an air gap with said one center leg segment adjacent the other end of said center leg, the other of said yoke members having one of its end legs abutting said other center leg segment adjacent said other end of said center leg and its other end leg defining another air gap with said other center leg segment adjacent said one end of said center leg, each of said yoke members having a leakage leg respectively abutting said center leg segments and defining a single coil receiving window with said air gap defining end leg and a double coil receiving window with said abutting end leg, a primary coil on said center leg and adapted to be connected to an external source of alternating current, said primary coil being positioned in said double coil receiving window of both of said yoke members, a first secondary coil on said center leg positioned in said single coil receiving window of said one of said yoke members and in said double coil receiving window of said other yoke member, and a second secondary coil on said center leg positioned in said single coil receiving window of said other yoke member and in said double coil receiving window of said one yoke member.
